To all whom it may concern:

Be it known that J. Henry Fry, of Cincinnati, Hamilton County, Ohio, have invented or produced, a new Ornamental Design for a Mole Trap, of which the following is a full clear and exact description, reference being had to the annexed drawings, making part of this specification, and in which one half of the ornamentation is represented by a front view (the other half being counterpart.)

(a), is a scroll, supporting the torus (b) of a fluted column (c), surmounted by a tulip formed capital (d). Upon this capital rests a four sided panel (e), having its center ornamented by a rosette (f).

The arched portion is decorated by a scroll work (g).

I claim as new and of my invention the Ornamental Design for a Mole Trap substantially as herein described and represented.

In testimony Whereof, I hereunto set my hand before two subscribing witnesses.
